UNITED STATES PATENT OFFICE

128,985

DESIGN FOR A COMBINED TIE CLIP AND EXTENSION PENCIL

Jacob M. Weiss, New York, N. Y.

Application December 14, 1940, Serial No. 97,298

Term of patent 7 years

To all whom it may concern:

Be it known that I, Jacob M. Weiss, a citizen of the United States and a resident of the city of New York, in the county of Kings and State of New York, have invented a new, original, and ornamental Design for a Combined Tie Clip and Extension Pencil, of which the following is a specification, reference being had to the accompanying drawing forming a part thereof.

Fig. 1 is a side elevation of a combined tie clip and extension pencil showing my new design.

Fig. 2 is a front elevational view thereof.

Fig. 3 is a rear elevation of the combined tie clip and extension pencil.

Fig. 4 is a plan view of the elements of the design separated from each other, the pencil being in an extended position.

The pencil is shown in a collapsible position in Figs. 1, 2 and 3.

I claim:

The ornamental design for a combined tie clip and extension pencil, substantially as shown and described,

JACOB M. WEISS.
